UNITED STATES PATENT OFFICE

FREDERICK W. C. NEUNER, OF CONNERSVILLE, INDIANA, ASSIGNOR TO INDIANA LAMP CORPORATION, OF CONNERSVILLE, INDIANA, A CORPORATION

LAMP CONSTRUCTION

Application filed November 24, 1925. Serial No. 71,117.

This invention pertains to a multiple light such as a combination tail light and spotlight or combination tail light, spotlight and back-ing light.

The particular feature of the invention resides in the construction of the lamp, and particularly the contact member for providing separate and distinct contacts between the connecting plug and several lamps.

Heretofore it has been the practice in such structures to employ connecting plugs slidably mounted with the usual bayonet slot connection having a pair of spring pressed contact pins for yieldingly making contact with the lamps, said plugs containing spiral springs and suitable tubes or sleeves in which the pins are slidably mounted. This type of spring contact has been found to be unfit by reason of the sliding pins sticking or becoming rusted or the springs losing their resiliency by reason of exposure to the weather.

The principal object of this invention is to provide a contact member which may be used in connection with a plug having rigid contacts thereon so as not to be dependent upon the usual sliding spring pressed contact pins mounted in the plugs.

The full nature of the invention will be understood from the accompanying drawings and the following description and claims.

Fig. 1 is a central vertical section through a combination stop and tail light. Fig. 2 is a section taken on the line 2—2 thereof. Fig. 3 is a sectional view taken on line 3—3 of Fig. 1 and in the direction of the arrows. Fig. 4 is a central section through a modified insulation contact illustrating an additional spring contact. Fig. 5 is the same as Fig. 2 showing a modified form having three contacts in place of two.

In the drawings there is shown a combination tail and stop light having a casing 10 supported on a vehicle by the screws 12. Mounted in the casing 10 there is a reflector 14 for the stop light bulb 15, the same being positioned within an upper compartment which is separated from the lower compartment by the partition plate 16. The lower compartment comprises a downwardly extending tongue 17 in which a tail lamp 18 is mounted.

The back of the casing is provided with the usual bayonet slotted sleeve 19 for receiving a contact plug 20.

It will be noted herein that the contact plug 20 is provided with two fixed contacts 21 instead of the usual spring pressed yielding cushion contacts commonly employed for this purpose.

The partition member 16 is cut away at the rear as shown in Fig. 3 leaving a pair of ears 22 in which a contact supporting floating connector 23, formed of insulating material such as fibre, is slidably supported by having a pair of oppositely disposed slots 24 formed in its periphery so as to embrace the inner edges 60 of the ears 22 as illustrated wherein it will have a loose fit so as to give it a floating or universal movement. Mounted on the floating connector 23 there is a pair of oppositely disposed spring contact plates 25 which are riveted thereto and extend a substantial distance from the periphery thereof in position to engage and make contact with the lamps 15 and 18. It will be noted that said contact plates are formed with a U-shaped bent portion 26 arranged to add to its spring action. Said plates are secured to the supporting disc by suitable contact rivets 27 adapted to be engaged by the contact members 21 on the plug 20.

From the above described structure it will be apparent that while the floating connector 23 is guided or partially supported by engagement of its slots 24 with the ears 22 formed in the partition 16, there is such a loose fit as to permit rocking motion either laterally or longitudinally of the plane through said slots. With this floating contact disc, a plug 20 with rigid contacts 21 may be employed by locking it in position where- 65 in it will engage the contact rivets 27, forcing the disc inwardly against the tension of the spring-like contact plates 25, the floating action of the floating connector being sufficient for all contacts to be made under the 70 spring tension afforded thereby.

In the modified form shown in Fig. 4, the structure and principle above set forth is the same with only the exception that the spring contact plates 125 are arranged to extend 100

through suitable openings in the floating connector so as to provide additional spring contact members 126 on the other side thereof in position to engage the fixed contacts 21 of the contact plug.

5 As illustrated in Fig. 5 the floating connector 223 may be provided with three spring contact plates 225 which will operate in the same manner as above set forth for giving resilient spring contact for use in connection with such lamps having additional signal lights or a backing light.

10 The invention claimed is:

15 1. A lamp structure comprising a casing and a plurality of lamps therein having electric contacts, a support for said lamps mounted in said casing including a pair of ears formed thereon, a contact plug having a plurality of fixed contacts thereon facing the contacts of said lamps, an annular flat insulating disc provided with lateral slots in its periphery, said slots loosely embracing the ears on said lamp support whereby said disc will be slidably mounted thereon and held 20 against transverse displacement between said plug and lamps, and a plurality of spring contact plates secured to said disc with the ends thereof extending outwardly in position to engage the contacts of said lamps, and 25 the other ends thereof bent rearwardly from said disc and curved toward each other so as to form a spring-like contact for engagement with the respective fixed contacts on said plug whereby said disc will be resiliently 30 mounted against longitudinal displacement and make electric contact between said plug and lamps.

35 2. A lamp structure comprising a casing having an open front and closed back provided with a socket forming opening to receive a contact plug, socket means in said casing, for supporting a plurality of lamps in substantially parallel relation on opposite sides of said plug receiving opening with 40 their center contacts toward the back of the casing, a floating connector including an insulating body provided with contacts, each for cooperating with a lamp and plug end contact, located between said lamp socket means 45 and said socket forming opening, said lamp structure also including means for slidably and rockably mounting said floating connector, said connector including means producing a resilient electrical connection between the lamp and the plug contacts.

50 3. A floating connector member comprising a disk of insulating material, contacts projecting from one face of said disk and cooperating contacts projecting radially from 55 the disk on the opposite side, certain of said contacts being resilient, said disk being provided with guiding slots in its edge.

60 4. A floating connector member comprising a disk of insulating material including 65 a member locating guide slot, and a contact

locating slot therein, a contact projecting radially from one face of the disk and secured thereto, and including a portion seated in the contact locating slot and extending therethrough and terminating upon the opposite face of the disk and approximately centrally thereof.

5 5. A device as defined by claim 3 characterized by the contacts of each group being similarly arranged and in spaced radial relation.

10 6. A device as defined by claim 4 characterized by the insulation disk including a plurality of contact locating slots and contacts, said slots and contacts both being arranged in spaced radial relation.

15 7. A lamp structure comprising a casing having an open front and closed back provided with a socket forming opening to receive a contact plug, socket means in said casing for supporting a plurality of lamps in substantially parallel relation and arranged in radial spaced relation relative to the axis of the socket forming opening and with their center contacts toward the back of the casing, a floating connector including an insulating body provided with contacts, each for cooperating with a lamp and plug end contact, located between said lamp socket means and said opening, said lamp structure also including means for slidably and rockably mounting said floating connector, the latter including means producing a resilient electrical connection between the lamp contacts and the plug contacts.

20 100 In witness whereof, I have hereunto affixed my signature.
